(No Model.)

G. W. CUSHING.
CAR DOOR FASTENER.

No. 337,929.

Patented Mar. 16, 1886.

UNITED STATES PATENT OFFICE.

GEORGE W. CUSHING, OF ST. PAUL, MINNESOTA.

CAR-DOOR FASTENER.

SPECIFICATION forming part of Letters Patent No. 337,929, dated March 16, 1886.

Application filed November 13, 1885. Serial No. 182,698. (No model.)

To all whom it may concern:

Be it known that I, GEORGE W. CUSHING, of St. Paul, in the county of Ramsey and State of Minnesota, have invented certain new and useful Improvements in Car-Door Fasteners, of which improvements the following is a specification.

The object of my invention is to provide simple and effective means for preventing sliding doors of freight-cars from being pried up and swung open, so as to enable car-thieves to gain admission without disturbing the usual side fastenings of the door or its seal.

The improvements claimed are hereinafter fully set forth.

In the accompanying drawings, Figure 1 is a side view in elevation of a freight-car door, illustrating the application of my invention; Fig. 2, an end view of the same; Fig. 3, a front view in elevation, and on an enlarged scale, of the bottom fastener; and Fig. 4, a side view of the same.

The door 1, to which my improvements are applied, is of the sliding type ordinarily employed in freight-cars, and works between upper and lower door tracks or rails, 2 3, which are secured to the plates 4, and side sills, 5, of the car in the usual manner, in this case being supported upon friction-rollers journaled in the brackets 8, and traversing on the lower track, 3.

As heretofore constructed, car-doors of such character have been fastened, when closed against their closed-door stops 6, by means of a side fastener, 7, which is locked by a padlock and seals. Under such construction the objection obtains that the door can be pried up and swung open at the side opposite the fastener 7, sufficiently far to enable access to be had to the interior of the car without breaking the lock of the side fastener, or disturbing its seals, so that robberies may be committed without any indication being afforded that the door has been tampered with, and their discovery be thus delayed until too late to trace and detect the persons by whom they have been committed. To obviate such objection, I provide a bottom fastener by which the lower portion of the door is secured to the body of the car adjacent to the side of the door opposite to that on which the usual side fastener is located, so that the door, be-

ing locked at its opposite sides, cannot be opened without such operation being evidenced by the breakage of the seals. The 55 bottom fastener is composed of a locking-staple, 9, secured to and projecting from the side sill, 5, and having a slot near its outer end, adapted to admit the body of a sealing-bolt, 10, which is coupled by a chain, 11, to the 60 car-door, and is provided with an enlarged head or stop, 12, on its upper end, of diameter greater than the width of the slot on the locking-staple, so as to prevent it from being passed through the same, and with a slot, 13, 65 near its lower end, through which a sealing-wire may be passed. A bearing-plate, 14, is fixed to the door 1, above and in line with the locking-staple 9, and a hasp, 15, is hinged by a bolt, 16, to said plate, the hasp having a slot 7c near its lower end of proper size to pass freely over the locking-staple 9, and over a suspending staple, 17, fixed to the upper portion of the bearing-plate 14.

To fasten the door, the hasp 15 is swung 75 down over the locking-staple 9, and held thereby to by inserting the sealing-bolt 10 in the slot of the staple. The bolt 10 being then sealed through its slot 13, it will be seen that no movement of the door can be effected without 80 the removal of the bolt, which will be immediately detected by the breakage of the seal necessarily involved in such operation.

When not required to be used—that is, during such periods as the door is not to be locked—8: the hasp 15 is turned up over the suspending staple 17 of the bearing-plate 14, and held in position by inserting the sealing-bolt 10 therein, the hasp and sealing-bolt being thus kept out of the way and protected from liability 90 to be broken or detached.

The fastener, which is inexpensive in construction, can be readily applied to any sliding door, and in practice has been found to effectively obviate the objection existing in the 95 ordinary method of securing car-doors.

I do not herein claim, broadly, the combination, with a sliding car-door, of a side fastener, and a bottom fastener adapted to secure the lower portion of the door to the body of the car adjacent to the corner of the door which is farthest from the side fastener, but reserve the right to make application therefor within due season.

I claim as my invention, and desire to secure by Letters Patent—

The combination of a bearing-plate, a swinging hasp hinged thereto, and having a slot near its free end, a suspending staple fixed to the bearing-plate in position to be inclosed by the slot of the hasp when turned upwardly, and a

sealing-bolt having a head or stop of greater width than the slot of the suspending staple, substantially as set forth.

GEORGE W. CUSHING.
